(57) **CLAIM**

(30) **Foreign Application Priority Data**

The ornamental design for a USB (Universal Serial Bus) memory device, as shown and described.

May 12, 2020 (KR) 30-2020-0020668

(51) **LOC (13) Cl. 14-03**

DESCRIPTION

(52) **U.S. Cl.**

FIG. 1 is a front perspective view of a USB(Universal Serial Bus) memory device;

USPC **D14/480.5**

FIG. 2 is a front view thereof;

(58) **Field of Classification Search**

FIG. 3 is a rear view thereof;

USPC D14/480.1-480.7, 435.1, 411, 433, 436,
D14/484.1, 137, 155, 203.1-203.8, 240,

FIG. 4 is a left-side view thereof;

D14/242, 496, 474; D13/133, 154

FIG. 5 is a right-side view thereof;

CPC H05K 5/0278; G06K 19/07732

FIG. 6 is a top plan view thereof;

See application file for complete search history.

FIG. 7 is a bottom plan view thereof;

(56) **References Cited**

FIG. 8 is another front perspective view showing a state
where the cap is inserted into the body.

U.S. PATENT DOCUMENTS

FIG. 9 is a front view of FIG. 9;

D513,005 S * 12/2005 Kobayakawa D14/480.1

FIG. 10 is a rear view of FIG. 9;

D556,198 S 11/2007 Blankenship et al.

FIG. 11 is a left-side view of FIG. 9;

D706,278 S * 6/2014 Fukuoka D14/480.5

FIG. 12 is a right-side view of FIG. 9;

D708,188 S * 7/2014 Erickson D14/480.1

FIG. 13 is a top plan view of FIG. 9;

D718,773 S * 12/2014 Erickson D14/480.1

FIG. 14 is a bottom plan view of FIG. 9; and,

D719,170 S * 12/2014 Gao D14/480.1

FIG. 15 is an exploded view thereof.

D719,171 S * 12/2014 Erickson D14/480.1

The evenly dashed broken lines in the figures depict environmental subject matter and form no part of the claimed design.

D724,600 S * 3/2015 Hsieh D14/480.1
